UNITED STATES PATENT OFFICE.

HUGO HORNICK, OF ROCHESTER, NEW YORK.

STROPPING DEVICE FOR SAFETY-RAZOR BLADES.

1,208,318.

Specification of Letters Patent. Patented Dec. 12, 1916.

Application filed July 9, 1914. Serial No. 849,942.

To all whom it may concern:

Be it known that I, HUGO HORNICK, of Rochester, in the county of Monroe and State of New York, have invented a new and useful Improvement in Stropping Devices for Safety-Razor Blades, which improvement is fully set forth in the following specification and shown in the accompanying drawings.

0 The present invention relates to stropping devices for safety razor blades and an object thereof is to provide a construction by which a safety razor blade may be secured and held in proper position to have its edge or edges stropped on an ordinary strop, the construction being such that the securing means for the clamping members may readily move over the strop without scratching or cutting the latter.

10 To these and other ends, the invention consists in certain parts and combinations of parts all of which will be hereinafter described, the novel features being pointed out in the appended claim.

25 In the drawings: Figure 1 is a plan view of the stropping device with a double edged blade therein; Fig. 2 is an enlarged view showing the clamping members in open position; Fig. 3 is a still larger view showing 30 the clamping members held together by the securing device, the parts being in longitudinal section on the line *a*—*a*, Fig. 1; Fig. 4 is a section on the line *b*—*b*, of Fig. 1; and Fig. 5 is a perspective view of the securing 35 device.

In the illustrated embodiment of the invention, there is employed a handle 1 made in any suitable manner and having a clamping member 2 extending in the direction of 40 the length of the handle and preferably rigid and integral therewith. There may also be provided a movable clamping member 3 which preferably is pivoted at 4 to the handle at a point near the inner end of the 45 rigid clamping member 2. Both of these clamping members are in the form of plates having their opposed faces flat and their outer faces curved transversely. From the flat face of the rigid clamping member, two 50 posts 5 extend, these posts being preferably in the form of semicircles in cross section and having their curved faces disposed toward each other. The movable clamping plate has two openings corresponding to the 55 cross sections of the posts so as to receive the posts when a blade, such as a double edged

blade with two circular openings, is fitted over said posts.

A feature of this invention is the provision of a fastening or securing device which 60 will hold the clamping members together at their free ends while at the same time not interfering with the passage or movement of the device over a strop. This securing or fastening device is in the form of a bifurcated member 7 having its two arms 8 formed at their free ends with opposed curved or beveled portions 9 while the outer faces of said arms are flat. The bifurcated member may also be provided with notches 65 10 forming shoulders which permit the fingers of a user to readily remove the fastener from the clamping members or facilitate the fitting of the fastener to such members. The inner faces of the bifurcated fastening or securing device coöperate with the outer faces 70 of the clamps near the free ends of the latter and hold the clamps upon the blade 6. To the end that the outer faces 8 of the securing or fastening device 7 will lie flush with the 75 outer faces of the clamping members, the outer faces of the clamping members are provided with pockets or recesses 11 which conform substantially to the proximate faces 80 of the arms 8 of the fastening or securing device so that said arms are received within the pockets 11. This arrangement also prevents the fastening device from being shifted laterally on the clamping members during 85 the action of stropping.

In the use of the device, a double edged or other blade having two circular openings is fitted over the post 5 after which the clamping plate 3 is moved to clamp the blade 95 against the clamping member 2. The fastening device then has its arms 8 introduced into the pockets 11 so that the clamping members are held in clamping position. The blade may now be moved back and forth over the strop and the fastening device is 100 so mounted that it does not present any sharp edges or projections which would interfere with the stropping action. The pockets which receive the fastening device not only serve to make the latter flush with the outer faces of the clamping members, but they prevent the lateral movement of the 105 fastening device on the clamping members. The semicircular posts prevent movement of the blade between the clamping members and 110 at the same time make it easy to fit the blade of the posts.

Having thus described my invention, what I claim is:

- A stropping device comprising a handle, a pair of blade clamping members supported at one end of the handle and having their longitudinal axes extending in the direction of the length of the handle to receive a blade between them, the free ends of the blade clamping members each being provided with a pocket on its outer face opening at the outer end of the member and of less width than the member, and a separable bifurcated fastening device extending around the free ends of the clamping members to ex-

pose both sides of the members so that a 15 double-edged blade may have both its edges exposed, said device having its arms slidably engaged within said pockets and removable in the direction of the length of the handle, the outer faces of said arms being flush with 20 the outer faces of the blade clamping members, the pocket serving to prevent the lateral movement of the fastening device under the stropping action.

HUGO HORNICK.
